LABELED OPEN-MESH BAG

Charles V. Brady and August F. Ottinger, St. Louis, Mo., assignors to Bemis Bro. Bag Company, St. Louis, Mo., a corporation of Missouri

Application December 4, 1948, Serial No. 63,548

8 Claims. (Cl. 150—1)

1

This invention relates to labeled open-mesh bags, and more particularly, to a banded label type of such bags.

Among the several objects of the invention may be noted the provision of an open-mesh bag presenting a relatively large, unbroken label area; the provision of a water-resistant bag of the class described embodying a water-resistant label firmly secured thereon; and the provision of a labeled bag such as described which is relatively inexpensive to manufacture. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which several of various possible embodiments of the invention are illustrated,

Fig. 1 is a plan view of a web from which an open-mesh bag of this invention is made, with parts peeled away;

Fig. 2 is a plan of the finished bag made from the web of Fig. 1, with parts peeled away;

Fig. 3 is an enlarged section taken on line 3—3 of Fig. 2;

Fig. 4 is an enlarged fragment of the bag web of Fig. 1;

Fig. 5 is a plan view of an alternative embodiment of the invention, with parts peeled away;

Fig. 6 is an enlarged section taken on line 6—6 of Fig. 5; and

Fig. 7 is an enlarged fragment of the bag web of the Fig. 5 bag.

Similar reference characters indicate corresponding parts throughout the several views of the drawings.

The word "open-mesh," as used in the specification, is intended to denote a fabric having the strands thereof spaced from one another a distance several times the strand diameter. While open-mesh fabric is often desirable for use as bag material, particularly for purposes of ventilation and visibility, the provision of a low-cost bag having a suitable label area has presented difficulties. One solution to the problem has been to provide a relatively closely woven area in the bag fabric adapted to have directly printed label indicia. However, the additional fabric strands required in the label area add to the cost of manufacture. Also, the printing itself is blurred and readily subject to distortion, particularly when the bag

2

is filled with lumpy objects, such as vegetables or fruit.

Another solution to the difficulties has been to weave paper ribbon into an open-mesh fabric to fill the interstices and provide a label area composed in part of paper and in part of fabric strands. In this case, the paper-weaving operation is costly, and the uneven label surface is difficult to print on.

10 Referring now more particularly to Figs. 1—4, there is shown an open-mesh leno-type bag 1 of this invention. Generally, the bag comprises a rectangular blank of open-mesh bag material folded upon itself along a central fold 3, and seamed at the marginal side edges 5 opposite the fold 3 and at one end 7. The other end or bag mouth 9 is reinforced and has an interwoven draw string 11. A label 13 peripherally encircles the girth of the bag extending around the fold 3 and being caught at its ends 15 in the side seam 5.

Initially, the open-mesh bag material is in the form of a longitudinal web 17 of a width corresponding approximately to the length of the finished bag. This consists of a water-resistant fibre 25 yarn woven partially into a plain weave, characterized in the drawings by relatively light lines; and partially into an open leno weave, the longitudinal warp strand pairs of the latter being characterized by relatively heavier lines. Though other material may be employed, the bag of this invention is particularly suitable for weaving from a twisted kraft-paper strip rendered water-resistant by chemical treatment. Extending transversely across the web 17 (or lengthwise of the finished bag) are uniformly spaced filler strands 19, which are dyed prior to weaving for improved appearance where exposed to sight. A selvage 21 is formed along one edge of the web to prevent raveling, which selvage ultimately appears at the bag mouth 9. The draw string 11 is woven into the web adjacent the selvage 21.

As previously mentioned, the warp strands are in different regions woven in different weaves, there being a central band of spaced plain-woven 45 warp strands 23 and adjoining areas of spaced leno-woven warp strand pairs 25 the yarn count in the band, as to the warp yarns, being substantially less than the warp yarn count in the remainder of the fabric. The respective filler and 50 warp strands 19, 23 and 25 are equally spaced from one another distances several times their diameter to provide square interstices 27. If the filler 19 is dyed, it is preferable to have similarly dyed warp pairs 25 in the leno-woven areas, though the plain-woven warp 23 need not be dyed.

The leno-woven areas extend to the edges of the web where there are additional strengthening warp pairs 29. Leno weave is used in the customary meaning of a pair of strands; each pair being intertwined between each of the filler strands. Each warp strand pair is spaced from the adjacent warp strand pairs a distance several times the diameter of the strands. Thus, while as to each warp strand pair, the two individual strands thereof are in engagement, each pair may be regarded as a strand, the pairs being spaced apart in open-mesh relation.

The bag label 13 is formed from a strip of paper label material which initially may or may not bear suitable advertising indicia. The label strip is centrally positioned upon the web over the plain-woven band 23, the width of the strip being sufficient to cover this plain-woven area. A water-resistant adhesive 33 covers the rear face of the strip to secure it to the web throughout its area and render it water impervious from its web side. Thus, the plain-woven strands beneath the label strip are secured against displacement by adhesive engagement with the label. The colored leno-woven areas on opposite sides of the label are exposed to view. The uncolored warp strands under the label strip are shielded from view.

It will be clear that the composite web may be manufactured in a substantially continuous manner by continuously combining a continuous supply of open-mesh web with a continuous label strip. The composite web may then be taken up in a roll, the tension therein compressing the label tightly to the strands so that there is substantial adhesive engagement along each strand, as indicated at 35 (Fig. 6). Under compression, the label tends to assume a wave shape bending around the strands and into the interstices 27. Bag blanks of approximately twice the desired bag width are cut from the web. The bag blank is folded upon the central fold 3 with the label 13 on the outside so that the marginal edges are adjacent one another. An inturned seam is formed along the marginal edges at the side 5 and end 7 which is secured as by stitching 37. The ends 15 of the label strip are turned inward with the web side edges to which they are secured and are thereby caught by the stitching 37. The ends 39 of the interwoven drawn string 11 are also caught by the stitching 37 and by an additional line of stitching 41. As mentioned previously, the label strip 13 may have the label indicia printed thereon prior to combining with the web, or at any stage in the manufacture thereafter.

In Figs. 5-7, there is illustrated an alternative embodiment of the invention. The bag 43 is formed from a blank of open-mesh bag material folded upon itself with side and bottom seams 45 and 47. A centrally positioned label 49, as described above, encircles the bag girthwise, being caught at its ends by the side seam 45.

As before, the bag blank is cut from a longitudinal web of open-mesh material having a label strip secured thereto throughout its area by a water-resistant adhesive 51. The open-mesh fabric of this embodiment is uniformly woven throughout substantially its entire area in an open plain weave, the strands 53 thereof being uniformly spaced from one another a distance several times their diameter. A twisted kraft-paper strip chemically treated with a waterproofing agent has been found satisfactory for the strand material. If desired, the areas of open-

mesh fabric exposed on opposite sides of the label may be dyed for improved appearance.

During the manufacture of this bag, the bag blanks are cut from the composite web, folded with label inside and stitched at the side and end marginal edges. The bag is then reversed to present the label on the outside and provide in-turned seams 45 and 47 with hidden stitching. Other forms of edge closures may be employed.

10 In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. A bag comprising a bag body of open-mesh fabric which is characterized in having been woven so as to have a band wherein the yarn count, as to those yarns which extend lengthwise of the band, is substantially less than the yarn count in the remainder of the fabric, and a label strip having a width corresponding to the width of said band peripherally encircling the bag body on the outside thereof over said band and adhesively secured thereto.

20 2. A bag comprising a bag body of open-mesh fabric which is characterized in having been woven with warp yarns and filler yarns and with a band extending in warpwise direction wherein the warp yarn count is substantially less than in the remainder of the fabric, and a label strip having a width corresponding to the width of said band peripherally encircling the bag body on the outside thereof over said band and adhesively secured thereto.

30 3. A bag comprising a bag body of open-mesh fabric which is characterized in having been woven with a plain weave band intermediate its edges and with a special weave on opposite sides of said plain weave band wherein warp yarns are paired instead of being single as in the plain weave band, and wherein the spacing of the pairs of warp yarns is generally the same as the spacing of the single warp yarns in the plain weave band, the filler yarns being common to both the plain and special weaves, and a label strip having a width corresponding to the width of the plain weave band peripherally encircling the bag body on the outside over the plain weave band and adhesively secured thereto.

40 4. A bag comprising a bag body of open-mesh fabric which is characterized in having been woven with a plain weave band intermediate its edges and with a leno weave on opposite sides of said plain weave band, the leno weave having paired warp yarns which are intertwined between the filler yarns of the fabric, the filler yarns being common to both the plain and leno weaves, the paired warp yarns of the leno weave being spaced generally the same as the single warp yarns of the plain weave, and a label strip having a width corresponding to the width of the plain weave band peripherally encircling the bag body on the outside over the plain weave band and adhesively secured thereto.

5. A bag comprising a bag body of open-mesh fabric which is characterized in having been woven with a plain weave band intermediate its edges and with a special weave on opposite sides of said plain weave band wherein warp yarns are paired instead of being single as in the plain

weave band, and wherein the spacing of the pairs of warp yarns is generally the same as the spacing of the single warp yarns in the plain weave band, the filler yarns being common to both the plain and special weaves, and a label strip having a width corresponding to the width of the plain weave band peripherally encircling the bag body on the outside over the plain weave band and adhesively secured thereto, the band and the label strip extending girthwise around the bag body.

6. A bag comprising a bag body of open-mesh fabric which is characterized in having been woven with a plain weave band intermediate its edges and with a leno weave on opposite sides of said plain weave band, the leno weave having paired warp yarns which are intertwined between the filler yarns of the fabric, the filler yarns being common to both the plain and leno weaves, the paired warp yarns of the leno weave being spaced generally the same as the single warp yarns of the plain weave, and a label strip having a width corresponding to the width of the plain weave band peripherally encircling the bag body on the outside over the plain weave band and adhesively secured thereto, the band and label strip extending girthwise around the bag body.

7. A bag comprising a bag body of open-mesh fabric which is characterized in having been woven so as to have a band of predetermined width wherein the amount of yarn material extending lengthwise of the band is substantially

less than the amount of yarn material extending lengthwise in like widths in the remainder of the fabric, and a label strip having a width corresponding to the width of said band peripherally encircling the bag body on the outside thereof over said band with the ends of the label strip secured in a bag seam.

8. A bag as set forth in claim 7 wherein the label strip is formed of paper and is adhered to the open-mesh fabric by a water-resistant adhesive covering the entire area of the label strip next to the open-mesh fabric.
